B. S. SMITH.

APPARATUS FOR THE WET DRESSING OF SULFID ORES,
APPLICATION FILED FEB. 11, 1913.

1,136,622.

Patented Apr. 20, 1915.

UNITED STATES PATENT OFFICE.

BENJAMIN SEDGELY SMITH, OF SYDNEY, NEW SOUTH WALES, AUSTRALIA.

APPARATUS FOR THE WET DRESSING OF SULFID ORES.

1,136,622.

Specification of Letters Patent. Patented Apr. 20, 1915.

Application filed February 11, 1913. Serial No. 747,646.

To all whom it may concern:

Be it known that I, BENJAMIN SEDGELY SMITH, subject of the King of Great Britain and Ireland, residing at 9 Jamieson street, Sydney, New South Wales, Australia, have invented certain new and useful Improvements in Apparatus for the Wet Dressing of Sulfid Ores, of which the following is a specification.

- 10 My invention relates to an improved apparatus for the wet dressing of sulfid ores, and is more particularly concerned with a type of apparatus employing a concentrator, combined with means by which the ore is graded and from which it passes to the concentrator in such a manner that the finer metalliferous products will be permitted to float without interference from the naturally submergible portions of the ore.
- 20 In a preferred form of my invention, I interpose between the grading means and the concentrator, suitable means for checking the momentum of the ore particles which fall to the concentrator from the grading means.

Several forms of my invention are illustratively exemplified in the accompanying drawing, in which—

Figure 1 is a sectional elevational view of one form of the invention; Fig. 2 is a similar view of a modified form in which the ore grading means is curved; Fig. 3 is a fragmentary sectional elevational view illustrating a modified form of invention in which a plurality of concentrators is set in vertical echelon order in relation to the grading means; and Fig. 4 is a fragmentary plan view, parts being broken away, in which a grading screen is arranged across 40 a plurality of concentrators arranged in lateral order.

The present invention is not concerned specifically with the construction of the concentrating table; it is applicable to any form of concentrator in the form of a table or flume carrying a flowing body of liquid on to which finely ground ore is dusted or sprinkled or fed gently and the submerged product separated from the floatage by any 50 effective means.

In the form of concentrator shown, a film or thin sheet of water flows rapidly over an inclined table the water feed head box being fitted with a squirt lip to accelerate 55 the water flow; at the foot is a sump box terminating below in a take off pipe with

suitable valve; the distant side of this box forms a weir over which the water carrying the float stuff flows.

Throughout this specification the concentrator has been described as an apparatus operated by flowing water, but it is my intention that it be construed to include also any such concentrator in which mobile liquids other than water are used, or aqueous 60 solutions of salts are used, so long as such concentrator be of the type in which the separation sought is obtained by the flotation of one portion of the ore substance and the submergence of other portions thereof. 65 Similarly the term "water" wherever used in this specification shall be construed to include mobile liquids or solutions of salts usable in the types of concentrator described.

Referring to Figs. 1 and 2, 1 is the concentrator which as shown consists of an inclined table over which water flows evenly from head to foot without turbulence. At the head a water box 3 with squirt lip 4 is fitted for the purpose of distributing 80 across the width of the concentrator the inflowing water which is received through the valved pipe 2. The surface stratum of water, which carries the floats passes over the weir 5 of the concentrator while the 85 lower stratum of water carrying with it the submerged material passes into the sump box 6 and away through a pipe 7 which is fitted with a suitable valve 8. The sump box 6 is constructed to the full width of 90 the concentrator. 18 is a hopper into which the mill product is delivered and from which the same is passed on to the upper end of the inclined grading screen 9 or onto the upper 95 end of the curved screen 9a. The bottom of this screen is clothed with wire gauze and the frame of the screen is supported on suitable flexible metallic supports, for example battens 10 hung from an overhead construction. The flexible supporting structure for 100 the grading screen is provided in order that such screen may be vibrated by any approved means (not shown) well-known in this art.

The wire gauze clothing on the screen 9 105 should be of finer gage toward the head of the screen than toward the foot thereof but if the feed be thick or if the angle of inclination of the screen be high the screen will differentiate the ore particles and pass 110 the finer particles first and the relatively coarser particles at a later stage.

The course of the water flow is indicated by the arrow, Fig. 1, and it will be observed that the finer particles which pass through the screen near the head thereof drop into the concentrator down stream while the coarser particles fall into the concentrator nearer the head thereof, successively in order of size of particles.

In Figs. 1 and 2, 14, 15, 16 and 17 are distributing screens below the grading screen; the distributing screens 14 to 17 form the bottom of compartments which preferably are subdivided by transverse partitions 19 and they are located just above the water surface so that ore particles falling through them will not acquire any considerable momentum before they come in contact with the water. These distributing screens may be clothed with wire gauze of varying mesh corresponding with the grade of ore falling onto different parts of them, or they may be clothed with gauze of a uniform mesh so long as the mesh be fine enough to arrest momentarily the falling ore particles and thereafter permit them to fall gently through the gauze onto the water surface immediately below.

When the grading screen 9^a is curved as shown in Fig. 2 it is not essential to clothe it with different gages of gauze; clothing with a uniform gage of gauze will operate quite satisfactorily in the case of a curved screen, because the screen will differentiate the ore particles and pass only the very finest near the head and so on in order to the coarse particles near the tail of the screen, the several distinct grades of particles falling on to the supplementary screens below and being delivered thence to the water.

Referring to Fig. 3 a plurality of concentrating tables 20, 21, 22 are arranged in vertical echelon order and the grading screen 9^c set above this group of concentrators so that the screen products

fall according to their gage into the several concentrators respectively and are separately treated therein. The screen 9^c shown in this figure may have fitted to it distributing screens 23 such as described with reference to Figs. 1 and 2. The speed of the water through the several concentrators 20, 21 and 22 may be varied to best suit the treatment of the particular gage of ore delivered by each section of said screen respectively.

In the arrangement shown in Fig. 4 the concentrating tables 31, 32, 33 are fixed in the same plane, side by side, and the grading screen 34 is fixed transversely over them.

What I claim as my invention and desire to secure by Letters Patent is:

1. In combination, a surface tension separating table provided with means for flowing liquid therethrough, a screen thereover adapted to deliver a predetermined size of material to the table, a distributing screen close to and parallel with the surface of the liquid on the table, interposed in the path of material dropping from the primary screen and adapted to break the momentum thereof.

2. In combination, a plurality of surface tension separating tables provided with means for flowing liquid therethrough, an inclined screen traversing the head ends of the separating tables and adapted to deliver progressively different sizes to the successive tables, and an intermediate distributing screen interposed in the path of each grade from the primary screen, parallel and close to the surface of the liquid in each table.

In testimony whereof I have affixed my signature in presence of two witnesses.

BENJAMIN SEDGELY SMITH.
